UNITED STATES PATENT OFFICE

152,461

DESIGN FOR A TOOTHBRUSH AND GLASS HOLDER

George E. Elliott, Birmingham, Ala.

Application October 18, 1946, Serial No. 134,044

Term of patent 7 years

(Cl. D4—3)

To all whom it may concern:

Be it known that I, George E. Elliott, a citizen of the United States of America, residing at Birmingham, in the county of Jefferson and State of Alabama, have invented a new, original, and ornamental Design for Toothbrush and Glass Holder, of which the following is a specification, reference being had to the accompanying drawing, forming part thereof, in which the figure is a perspective view, showing my new design.

I claim:

The ornamental design for a toothbrush and glass holder, as shown.

GEORGE E. ELLIOTT.
